United States Patent Office

Des. 222,655
Patented Nov. 23, 1971

222,655

COMBINED CONTAINER AND DISCS

Charles T. Inatomi, Culver City, and Jackson R. Iblings,
Manhattan Beach, Calif., assignors to The National Cash Register Company, Dayton, Ohio

Filed July 7, 1969, Ser. No. 18,067

Term of patent 14 years

Int. Cl. D3—99

U.S. Cl. D87—1

FIG. 1

FIG. 3

FIG. 1 is a top perspective view of a combined container and discs showing our new design, the portion of the handle not seen is reversely similar to that shown;

FIG. 2 is a bottom perspective view thereof, the circumferential side opposite being identical to the side shown;

FIG. 3 is a side elevational view thereof with the container shown in cross section and a portion of the discs broken away showing the handle.

We claim:

The ornamental design for a combined container and discs, substantially as shown and described.
